UNITED STATES PATENT OFFICE.

HERBERT L. HUNTER, OF CLEVELAND, OHIO.

PLUMB-LEVEL AND PROTRACTOR.

1,400,069.

Specification of Letters Patent. Patented Dec. 13, 1921.

Application filed June 16, 1920. Serial No. 389,434.

To all whom it may concern:

Be it known that I, HERBERT L. HUNTER, a citizen of the United States, residing at Cleveland, in the county of Cuyahoga and State of Ohio, have invented certain new and useful Improvements in Plumb-Levels and Protractors, of which the following is a specification.

This invention relates to a plumb level provided with an extensible stock, a dial, and means for illuminating the dial, the extension forming a cover which in closed position covers both the dial and the button controlling the illuminating means. That portion of the invention relating directly to said extension or cover is the subject matter of a divisional application filed February 1, 1921, and bearing Serial Number 441,527.

With these various objects in view the invention consists of the novel features of construction hereinafter described, pointed out in the claim, and shown in the accompanying drawings, in which:

Figure 1 is a front elevation, the casing sections being extended.

Fig. 2 is a section on the line 2—2 of Fig. 1.

Fig. 3 is a rear view, the casing being extended.

Fig. 4 is a section through the stock and dial showing a modified form.

Fig. 5 is a section on the line 5—5 of Fig. 3.

In constructing the device I employ a stock 1 which is preferably of wood and of any desired size. This stock is provided with a longitudinal groove 2 extending along its top and bottom edges, and placed midway the front and back faces of the stock. The stock is inclosed by a metal casing 3, formed in two sections, one of which slides on one end of the stock and the other on the opposite end of the stock, the sections when in closed position meeting midway the ends of the stock. These sections are provided with interior, longitudinal tongues 4 which slide in the grooves 2 of the stock.

The closed outer ends of the casing sections have secured in them inwardly extending pins 5 which work in suitable end bores formed in the stock. To lock the sections to the stock, either in extended or closed position, the following parts are employed. The back of the stock is provided with suitable transverse bores connecting with the bores in which the pins 5 work. In these trans-

verse bores I fit interiorly threaded sleeves 6 having a securing flange 7 which is countersunk into the face of the stock.

A screw 6^a works in each sleeve and is provided at its outer end with a thumb nut 8 and the casing sections are provided with slots 9 having beveled sides, in which said thumb nuts rest, the length of these slots regulating the sliding movement of the casing sections.

It will be obvious that when the nuts are turned down the screws will bear on the pins 5, thus locking the casing sections in adjusted position.

I set into the rear face of the stock a protractor 10.

In the central front face of the stock is formed a recess 11 and a transverse boss 12 is centrally arranged with respect to said recess, the boss being flanged and suitably secured to the back face of the stock. To the front end of the boss, and within the recess 11, is secured a circular dial plate 13, of a transparent material, the marginal portions of which are angled inwardly as shown at 14. A securing pin 15 extends through the boss and the dial plate is threaded onto the front projecting portion of said pin. Mounted on the boss, and back of the dial plate, is a pendulum 16 having an angled index finger 17, the angled portion working over the front face of the marginal portion of the dial, as shown most clearly in Fig. 2. The pendulum and its index finger is mounted on suitable ball bearings 18 placed on the boss 12.

To illuminate the dial face I form a recess 19 in the front of the stock and to one side of the recess 11, but communicating therewith. In said recess I place a flash light 20. The side margins of the recess are stepped or rabbeted and the recess is covered by a retaining plate 21 which holds the flash light in place. This plate has a slot 23 for the push button of the flash light to project through and work in, and the plate 21 is set in a sufficient distance so that the cover casing section on that end of the stock can slide over the button 22.

In Fig. 4 I have shown a modified form of dial plate.

In this form the plate 24 with its angled marginal portion 25 is set in the back of the recess and bears against the stock. The index member 26, including finger and weight is mounted in advance of the dial plate, on ball

bearings 27, and the central portion of the dial plate and parts of the index member are covered by a cover plate 28. All of these parts are set into the front face of the stock 5 and are covered and protected by the casing sections when in closed position.

When this form of dial is used it need not be of transparent material as the light is thrown on the front of the dial face instead 10 of on the back. Except for the reversal of the parts the two dial forms are substantially alike and operate in the same manner.

The use of levels of this kind is well known and the advantages of the construction above 15 described and shown in the drawings will be

apparent to those skilled in the manufacture and use of plumb levels and protractors.

What I claim is:—

The combination with a stock having communicating recesses, a dial arranged in one 20 recess, a weighted index finger for the dial, a flash light arranged in the other recess, a retaining plate covering said light and slotted to receive the flash light button, and a sectional casing slidable on the stock and adapted 25 when in closed position to cover said plate and button and the dial.

In testimony whereof I have affixed my signature.

HERBERT L. HUNTER.
